DISHWASHING MACHINE

William Bond, San Francisco, Calif.

Application August 1, 1955, Serial No. 525,564

5 Claims. (Cl. 134—172)

This invention is directed to improvements in dishwashing machines and is particularly directed to a water pressure dishwasher having a collapsible hood arrangement particularly adapted to doing large volumes of dishes but which may be folded up and easily put aside in a cabinet or drawer when not in use.

One of the primary objects of this invention is to provide an improved dishwashing machine having a collapsible top which may be readily swung up and over the dishes to be washed while at the same time providing adequate spray for the dishes both above and below the receptacle containing the dishes.

Still another object of this invention is to provide a full capacity dishwasher which may be folded up and put away with a minimum of space utilization.

Still another object of this invention is to provide an improved dishwashing machine with a novel top arrangement which may readily be swung up into operative position or withdrawn and folded downwardly for easy access to all the dishes in the apparatus.

Still another object of this invention is to provide an improved water pressure dishwasher particularly adapted for use on the sink top in conjunction with the regular sink in the kitchen and the like.

Further features and advantages of this invention will appear from a detailed description of the drawings in which:

Fig. 1 is a side elevation of a dishwashing machine incorporating the features of this invention.

Fig. 2 is an end elevation of the apparatus shown in Fig. 1.

Fig. 3 is a section on the line 3—3 of Fig. 2.

Fig. 4 is a section on the line 4—4 of Fig. 1.

Fig. 5 is a side elevation similar to that of Fig. 1 but showing the top in retracted position.

As an example of one embodiment of this invention there is shown a water pressure dishwasher having a main base pan 10 having a bottom 11 and the integral sides 12 and 13 and the ends 14 and 15. Suitable raised support brackets 16 fixed to the inside faces of the ends 14 and 15 carry the dish-holding basket 17 in which are placed the dishes to be washed.

The top edges of the sides and ends is formed by an upturned flange 18 forming a ledge 19 around the upper portion of the base pan 10. A collapsible cover is formed of a series of ribs 20, 21 and 22 pivotally mounted to swing around an axis 23 on the upturned flange 18 at the sides 12 and 13 of the base pan 10. Suitable plastic cover material is connected to the outside of the ribs at 24, 25, 26 and 27. The plastic material portion 24 is secured water-tight along its lower edge to the ledge 19 between the axis of rocking 23 and the end 14 of the base pan 10. The other portion is connected to the swinging hoop or rib 28 having the manipulating handle 29. The entire assembly of the ribs 20, 21, and 22 and the plastic 24, 25 and 26 and 27 may be swung up over the dishes in the basket 17 as shown in Fig. 1 or swung back down in retracted position as shown in Fig. 5 for removal of the

2

dishes and for storage of the unit with a minimum of vertical space requirement.

It is important to note that the water spray element 29a is fixed to the under side of the mid upper portion of the rib 21 as best shown in Figs. 3 and 4. A water supply conduit is formed at 30 and 31 integral with the rib 21 and in fact may preferably form said rib. It connects with a hinged fluid connection 32 with the pressure water supply pipe 33 which is preferably connected to the hot water tap at the sink. There is also a fixed discharge line 34 from the hinge fluid connection 32 extending to the horizontal supply line 35 which terminates at the mid point of the bottom 11 of the base pan 10 to supply the lower spray element 36 located under the dish basket 17.

Thus, with the dishes loaded in the basket 17 the hood may be swung up by manipulation of the handle 29 from the position shown in Fig. 5 to the position shown in Fig. 1 which automatically brings the water spray element 29a up centrally over the dishes. Water pressure is then turned on in the line 33 and both of the spray elements 29a and 36 go to work rapidly to rinse off the dishes. A suitable drain spout may be provided at 37 in the bottom of the pan 10 which discharges into the sink for removal of the excess water and foreign matter from the dishes as they are washed off by the spray elements 29a and 36. At the completion of the dishwashing operation the water is turned off and the cover swung down to the position indicated in Fig. 5 for easy access to the dishes. Furthermore, it may be folded down completely to the top of the upturned flange 18 and the dish basket 17 placed back in the regular sink or otherwise disposed of so that the entire dishwashing unit may now be easily slipped into a drawer or cupboard with a very minimum of height from the bottom 11 to the top of the upturned flange 18 of the unit.

Thus there has been provided a highly efficient table top dishwashing machine which is collapsible for easy storage and access to the dishes.

While the apparatus herein disclosed and described constitutes a preferred form of the invention, it is also to be understood that the apparatus is capable of mechanical alteration without departing from the spirit of the invention and that such mechanical arrangement and commercial adaptation as fall within the scope of the appended claims are intended to be included herein.

Having thus fully set forth and described this invention what is claimed and desired to be obtained by United States Letters Patent is:

1. A dishwashing machine including a readily portable base pan, a collapsible top mounted on the top edge of said pan having a series of ribs pivotally mounted to swing about a horizontal axis located midway the sides of said pan, a flexible waterproof cover mounted over the outside of said ribs having one end thereof secured to the top edge of said pan between one end of said pan and said pivotal axis, and a water spray element mounted on the inside of one of said ribs.

2. A dishwashing machine including a readily portable base pan, a collapsible top mounted on the top edge of said pan having a series of ribs pivotally mounted to swing about a horizontal axis located midway the sides of said pan, a flexible waterproof cover mounted over the outside of said ribs having one end thereof secured to the top edge of said pan between one end of said pan and said pivotal axis, a water spray element mounted on the inside of one of said ribs, said rib carrying said water spray element including an integral water supply conduit, and a hinge fluid connection on said pivotal axis connected to said conduit.

3. A dishwashing machine including a readily portable base pan, a collapsible top mounted on the top edge of

said pan having a series of ribs pivotally mounted to swing about a horizontal axis located midway the sides of said pan, a flexible waterproof cover mounted over the outside of said ribs having one end thereof secured to the top edge of said pan between one end of said pan and said pivotal axis, a water spray element mounted on the inside of one of said ribs, said rib carrying said water spray element including an integral water supply conduit, a hinge fluid connection on said pivotal axis connected to said conduit, a rigid conduit in said pan in communication with said hinge fluid connection, a dish basket carried in said pan adapted to be covered by said collapsible top, and a lower water spray element in said pan below said basket.

4. In a dishwashing machine, a base pan, a lower spray element mounted on the base pan in a horizontal plane and adapted to spray water upwardly, a dish holding basket removably mounted on the base pan to receive water ejected as a spray from the rotatable spray arm, a flexible collapsible cover adapted to be mounted on the pan to enclose the space over the pan, said cover being supported over the pan by at least one rib adapted to extend over the

15

10

20

pan in spaced relation to the basket mounted on the pan, and a waterspray element carried centrally on the rib and adapted to spray water downwardly onto dishes in the basket.

5. In a dishwashing machine, a base pan, a lower spray element mounted on the base pan in a horizontal plane and adapted to spray water upwardly, a dish holding basket removably mounted on the base pan to receive water ejected as a spray from the rotatable spray arm, a flexible collapsible cover adapted to be mounted on the pan to extend over the pan in spaced relation to the basket mounted on the pan, and a water-spray element carried centrally on said cover and adapted to spray water downwardly onto dishes in the basket.
